UNITED STATES PATENT OFFICE

2,471,508

KITCHEN CABINET WITH TABLE FORMING
FRONT

Senator W. Adams, Birmingham, Ala.

Application October 11, 1946, Serial No. 702,679

5 Claims. (Cl. 312—161)

1

My present invention relates to an improved cabinet and table combination, and more particularly to a kitchen cabinet in which the lower front wall thereof is hinged to the cabinet body and is adapted to be raised to horizontal position, thereby to form a table.

One object of my invention is to provide an improved latch means for holding the hinged front of the cabinet in locked position with respect to the body thereof when the front is not in use as a table.

Another object is to provide an improved cabinet of the character described in which a supporting leg member for the table front carries at one end a latch member for holding the pivoted front in vertical, wall forming position on the cabinet, and in which the leg itself is utilized for raising and lowering the front to and from table forming position.

A further object of my invention is to provide a combination kitchen cabinet and table in which the supporting leg therefor carries a latch member at its lower end adapted to cooperate with a fixed latch member on the cabinet, and which also is provided with a readily detachable fastening means for securing the free end of the leg to the cabinet.

A cabinet embodying features of my invention is illustrated in the accompanying drawings, forming a part of this application, in which

Fig. 1 is a front elevational view of a cabinet embodying my improved table front construction;

Fig. 2 is a side elevational view with the front pivoted outwardly and upwardly to form a table;

Fig. 3 is a sectional view taken along line III—III of Fig. 1;

Fig. 4 is a detail sectional view to an enlarged scale taken along line IV—IV of Fig. 3; and

Fig. 5 is a perspective view of the lower portion of the cabinet with the front thereof raised to form a table.

Referring now to the drawings for a better understanding of my invention, I show a cabinet 10 which may be of the usual type adapted particularly for installation in a kitchen. The cabinet embodies the upper shelf section 11, the work top 12, and the lower cabinet section 13. In the particular cabinet illustrated, I show the work top 12 projecting outwardly past the front of the cabinet, as illustrated at 14. The lower cabinet section 13 may be provided with the usual utensil drawers 16 and 17, and the usual shelves 18 and 19.

The lower section of the cabinet has the door frame 21 thereof formed in the shape of a U at its

2

top end, thereby to straddle the projecting work top 14, and is pivotally connected by means of hinges 22 and 23 to the cabinet. The U-shape of the door frame 21 is also continued as indicated at 24 to fit about the supporting frame work for the drawers 16 and 17. Mounted in the frame are the usual doors 26 and 27, provided with the usual snap detents 28 and 29. The doors are hinged in the manner well understood by hinges 31 to the frame 21. The hinges preferably are of the flush type, thus leaving the surface of the doors and frame free of outward projections.

From the foregoing, it will be apparent that the entire frame 21, including the doors 26 and 27, may be pivoted upwardly about the hinges 22 and 23 to form a table which is an extension of the work top 12. The U-shape of the frame 21 permits the assembly to move upwardly about the projection 14 of the top 12, and to lie in the same plane therewith.

The door frame is provided at its bottom with a slot 32. Mounted on a pin 33 is the lower end of a member 34, adapted when the doors and frame are horizontal to form a supporting leg therefor. As shown more clearly in Fig. 3, the leg 34 is provided at its pivoted end with an inwardly projecting portion 36 having groove 37 adapted to engage over a stationary latch member 38 fast on the floor 39 of the cabinet. The upper end of the leg 34 is provided with the male member 41 of a snap latch device, the female member 40 thereof being secured to a stationary portion 42 of the front wall of the cabinet. The slot 32 is long enough to permit rotation of the end 36 through the door frame 21 for a purpose later to be described.

From the foregoing, the construction and manner of using my improved cabinet table will be readily understood. When it is desired to form a table, the upper end of the leg 34 is unlatched by pulling the same outwardly as indicated by the arrow 43, Fig. 3, whereupon the inwardly projecting portion 36 of the pivoted end moves upwardly, thus to disengage the groove 37 from the latch member 38. The user now pulls the leg 34 upwardly with one hand, thereby lifting the entire front of the cabinet until the lower edge can be grasped in the other hand. The leg is now rotated counterclockwise as viewed in Fig. 3 to the position shown in Fig. 2 of the drawings, in which position the same rests upon the floor 44 and supports the free end of the door frame.

In order to provide sidewise rigidity for the leg 34, I may provide at each side of the slot 32 a

pair of guide blocks 46, secured to the inner side of the door frame by screws 47.

From the foregoing it will be apparent that I have devised an improved cabinet and table combination which is extremely simple of manufacture and construction and which is useful in providing table space in small kitchens. The particular arrangement of the leg 34 permits the front to be raised to table forming position without the necessity of the user having to stoop over and grasp the frame at its lower end. Also, it will be apparent that with the groove 37 engaged over the latch member 38, and the snap latch 41 in place, the entire front of the cabinet is securely latched to the body portion thereof. Also, it will be apparent that while I have shown but one leg a plurality thereof may be provided if desired, and my improved arrangement may be applied with equal facility to a cabinet which does not have the overhanging top portion 14.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In a cabinet embodying a door frame and doors therein forming a front for the cabinet, means to pivot the door frame at its upper end, a leg pivoted to the door frame adjacent the bottom thereof, a stationary latching member on the lower portion of the cabinet, and a complementary latching means carried by the pivoted end of said leg for engaging the stationary latching member to secure the pivoted frame to the cabinet.

2. In a cabinet embodying a door frame and doors therein forming a front for the cabinet, hinges pivotally connecting the upper end of the door frame to the cabinet, a leg member for supporting the frame and doors in horizontal, table-forming position, means to pivotally connect the leg to the free end of said door frame, a stationary latching member, complementary latching means carried by the leg at the pivoted end thereof and engageable with the stationary latching member to secure the free end of the door frame to the cabinet, and other latching means for securing the free end of the leg to the cabinet.

3. In a cabinet embodying a door frame and doors therein forming a front for the cabinet, hinges connecting the upper end of the door frame to the cabinet, a leg member for support-

ing the frame and doors in horizontal table-forming position, means to pivotally connect the leg to the free end of said door frame, an extension on the pivoted end of the leg adapted to project inwardly of the cabinet, there being a downwardly opening groove in said extension, an upwardly projecting lug on the cabinet adapted to fit into said groove thereby to removably secure the free end of the door frame to the cabinet, and snap latch means carried by the other end of the leg for removably securing the same to the cabinet.

4. In a cabinet embodying a door frame and doors therein forming a front wall for the cabinet, hinges connecting the upper end of the door frame to the cabinet, a leg member for supporting the frame and doors in horizontal, table-forming position, means to pivotally connect one end of the leg to the free end of the door frame, said leg being adapted to lie against the outside of the door frame when the frame is in wall forming position, a stationary latch member on the lower portion of the cabinet, an extension on the leg at its pivoted end adapted to project inwardly of the cabinet, there being a downwardly opening groove in said extension adapted to engage about the stationary latch member upon pivotal movement of the leg, and other latching means for securing the free end of said leg to the cabinet, thereby to hold the same against outward movement about its pivot.

5. In a cabinet embodying a work top having a portion overhanging the front thereof, a U-shaped door frame adapted to straddle the overhanging top portion, means to pivotally connect the legs of the U-shaped frame to the cabinet, doors in the frame, a supporting leg pivoted to the door frame adjacent the free end thereof, a stationary latching member on the lower portion of the cabinet, complementary latching means carried by the pivoted end of the supporting leg and engageable with said stationary member to latch the pivoted door frame in vertical position on the cabinet, and a snap latch carried by the supporting leg for latching the free end thereof to the cabinet.

SENATOR W. ADAMS.
